Patented Dec. 8, 1925.

UNITED STATES PATENT OFFICE.

ALEXIUS LOUGHAN, OF BROOKLYN, NEW YORK.

SANDSLINGER MACHINE.

Application filed September 1, 1923. Serial No. 660,468.

To all whom it may concern:

Be it known that I, ALEXIUS LOUGHAN, a citizen of the United States, a resident of Brooklyn, in the county of Kings and State 5 of New York, have invented a certain new and useful Improvement in Sandslinger Machines, of which the following is a specification.

This invention relates to an improvement 10 in sandslinger machines and it relates more particularly to a machine wherein the sand-slinger is stationary while the mechanism for supplying sand thereto is movable with respect to the sand pile.

15 In machines of this type wherein sand is thrown at very high velocity into a mold, it has been the practice to provide a very large quantity of sand and to feed this sand by suitable means to the so-called sandslinger 20 which is positioned above the molds so as to eject the sand therein at high velocity. Some of these machines have been stationary in which case the sand had to be fed thereto by suitable conveying mechanism, and some 25 of the machines have been of a movable tractor type in which the entire mechanism was transported or moved with respect to a long sand pile from which the moving tractor elevated the sand to the so-called 30 sandslinger.

The present invention relates in part to the latter type as it makes use of a movable tractor operating upon suitable tracks alongside of a sand pile, this tractor being adapted 35 to convey the sand from the sand pile in substantially the same manner as in the previous machines; but because of the stationary position of the sandslinger, mechanism has been devised to convey the sand delivered 40 by the movable tractor over to the sandslinger. The mechanism for thus conveying the sand and handling it to and from the sand pile, together with the mechanism for the other molding operations, form the particular subject of the present invention as 45 will more fully appear hereinafter from the following description of a preferred embodiment of the invention, which is given for the purpose of illustrating the same.

50 Fig. 1 of the drawings shows a plan of the apparatus and the sand pile with the sandslinger permanently stationed at one end of the sand pile, and the conveying

mechanism installed in relation to said sand-slinger and the sand pile; and

55 Fig. 2 shows a side view of the apparatus and sand pile.

In said preferred embodiment of the invention there is shown a long sand pile 1 of the usual shape, lying between tracks or 60 racks 2 and 3 upon which the movable tractor is adapted to travel. The latter is shown at 4 and is composed essentially, as far as the present embodiment is concerned, 65 of spiral conveyors 5 and 6 serving to move the sand inwardly from the tracks, and to an elevator 7 serving to elevate the sand from the pile; gear wheels or cog wheels such as 8 support the movable tractor and travel upon the said tracks. This part of the structure is well-known and need not be further described.

70 The sand is dumped from the top of the tractor on to a short belt 9 suitably supported by framework 10 upon the tractor, this belt 9 serving to convey the sand on to a belt 11 which may be of the type known as a movable endless belt conveyor. The latter 75 conveys the sand to the sandslinger 12 positioned as shown. Here the sand is screened 80 in the usual way by a screen 13 and conveyed therefrom by means of a belt 14 to the sandslinger proper 15 which rotates at a very high velocity and throws the sand violently 85 into the molds 16 which are conveniently 90 positioned around the sandslinger, the latter being movable with respect to the molds. The particular structure of the stationary sandslinger is well-known in the art and 95 does not form part of this invention.

When the molds have been filled they are 100 placed upon suitable cars such as 17 adapted to be moved along tracks 18, and these cars are provided with turntables 19 so that they may be turned around to facilitate loading and unloading and also to facilitate the sandslinging and casting operations.

105 The cars with the molds are moved down to the end of the track 18 and on to a car 20 having thereon tracks 21 upon which the car 17 is adapted to be moved. This car 20 is then brought in juxtaposition to a ladle 22 traveling upon a car 23 on tracks 24, the ladle receiving melted metal from 110 the cupola 25. The casting operation at 105 this point proceeds in the usual manner and

thereafter the car 20 is moved along the tracks 26 down to the position 27, at which point the car 17 is rolled off the car 20 on to tracks 28 and thence to a point about midway between the ends of the track.

At this point the cope is lifted from the car and the sand dumped into the pit 29 through a grating 30 while the drag is emptied on to a grating 31 vibrated by an eccentric 32, the sand passing through the grating into the pit while the castings fall in front of an elevator 33 which elevates them to a runway 34 down which they travel to a point of delivery 35. This particular form of mechanism 33 and 34 is designed for use in handling sash weights and will of course be varied according to the kind of castings made, and may be dispensed with altogether. The sand collected in the pit 29 is elevated by an elevator 36 and dumped on to a moving belt 37 from which it is in turn dumped on to a belt 38 which dumps it back on to the ground to re-form the sand pile. The said belt 38 may be shuttled back and forth according to whether it is desired to dump the sand on to the pile, the object being to re-form the pile back of the tractor as it moves forward, so that at the end of the run the sand pile will have been re-formed and ready for the ensuing operation when the tractor is moved thru the pile in the opposite direction as, for example, on the next day's run. The belt 38 may be operated from an electric motor with suitable connections to reverse the rotation of the belt when the rotation is to be changed at the time the sand pile is half formed. The cars 17, after the molds are again placed thereon, are run to the end of the track 28 and thence on to a car 39 running on a track 40 by which means they are conveyed back to the track 18 in position adjacent the sand-slinger ready for the resumption of the same operation.

The operation of the entire machine will now be clear from the description thereof and may be briefly stated to be as follows: The movable tractor is placed at one end of the sand pile and set in motion to convey sand to the belt 9 from which sand is delivered to the belt 11 and thence to the stationary sand-slinger. Here the molds are filled in the usual manner and are then placed upon the cars 17 and conveyed to the ladle mechanism where the casting is performed. The cars 17, riding upon the car 20, are then moved over to the track 28 and run along this track until they arrive adjacent the dumping apparatus. Here the sand is dumped out and the castings are removed from the molds. The latter are again placed upon the car and conveyed back to the track 18 ready for another operation. When the tractor arrives at the end of the sand pile it must be turned around and this

may be done by any suitable means such as a hydraulic lifting jack; the tractor can, however, be made rotatable so as to avoid turning it around.

It will be seen that by means of the invention above described the handling of the molds has been made quite simple inasmuch as they need not be carried but a short distance from the tracks by the workmen; and they are always positioned at one point in the system from which they are conveyed by cars and to which they are brought back by the same means. It will be furthermore apparent that the handling of the sand has been made quite simple in that it always remains on the ground when not being actually put in use, thus dispensing with the necessity for erecting expensive storing bins. The sand pile is re-formed as fast as it is used up so that when the tractor arrives at the end of the sand pile, as for example at the end of a day's run, the pile will be there ready for the next day's run, and the means effecting this consists simply in a series of belts which convey the sand from the dumping apparatus back to the sand pile, a simple shuttle belt being used to follow the tractor and dump the sand behind it. It will furthermore be apparent that an additional advantage consists in bringing the cars containing the molds adjacent the ladle. It should also be pointed out that the present invention economizes space and does not involve great expense.

As many apparently widely different embodiments of my invention may be made without departing from the spirit thereof, it is to be understood that I do not intend to limit myself to the embodiments described except as defined in the following claims.

I claim:

1. The combination of a stationary sand-slinger with means for conveying sand thereto from a sand pile, a dumping place for molds, and means for re-forming the sand pile as it is consumed comprising a sand conveyor for removing sand from said dumping place to the sand pile, and a conveyor for conveying sand from sand-slinger to the sand pile.

2. The combination of a stationary sand-slinger with means for conveying sand from a sand pile to said sand-slinger; means for re-forming the pile as it is consumed; and conveying means for the molds from the sand-slinger to a ladle, and thence to a dumping place, and back again adjacent the sand-slinger.

3. The combination of a stationary sand-slinger with means for conveying sand from a sand pile to said sand-slinger; means for re-forming the pile as it is consumed; and cars running on tracks laid around the sand pile for conveying the molds from the sand-slinger to the ladle, and thence to a dump-

ing place, and back again adjacent the sandslinger.

4. The combination of a stationary sandslinger with means for conveying sand from a sand pile to said sandslinger; means for conveying the molds from the sandslinger to a ladle, thence to a dumping place, and back again adjacent the sandslinger; and means for conveying the sand from the 10 dumping place back to the sand pile to replace the sand consumed.

5. The combination of a stationary sandslinger with means for conveying sand from a sand pile to said sandslinger; means 15 for conveying the molds from the sandslinger to a ladle, thence to a dumping place, and back again adjacent the sandslinger; and means for conveying the sand from the dumping place back to the sand 20 pile to replace the sand consumed, said means comprising a transverse and longitudinal shuttle belt.

6. The combination of a stationary sandslinger with means for conveying sand from a sand pile to said sandslinger; means 25 for conveying the molds from the sandslinger to a ladle, and thence to a dumping place, and back again adjacent the sandslinger; said dumping place being provided with a sand pit, an elevator for removing the sand therefrom, and belts for conveying the sand back to the sand pile.

7. The combination for use in connection with a sand pile, of a sand-elevating 30 means; a dumping place for the sand after having been used; and a shuttle belt above

the sand pile having means for delivering the sand thereto so that the sand may be dumped back on to the ground to re-form the sand pile.

40 8. The combination for use in connection with a sand pile, of a dumping pit; an elevator therein delivering sand to a transverse conveying means; and a longitudinally positioned shuttle belt for dumping the sand back on to the ground to re-form the sand pile.

45 9. The combination for use in connection with a sand pile, of tracks laid around the same and cars adapted to run on the 50 tracks; a ladle positioned adjacent the tracks; a sand dumping place positioned beside the tracks somewhat remote from said ladle; and means for conveying the sand from the dumping place back to the 55 sand pile so as to re-form the same.

10. The combination for use in connection with a sand pile, of tracks laid around the sand and cars adapted to run on the 60 tracks; a ladle positioned adjacent the tracks; a sand dumping place positioned beside the tracks somewhat remote from said ladle; means for conveying the sand from the dumping place back to the sand 65 pile so as to re-form the same; and a stationary sandslinger positioned adjacent another point along said tracks.

In testimony that I claim the foregoing, I have hereunto set my hand this 14th day of August, 1923.

ALEXIUS LOUGHAN.
